L. WERNWAG.

Car Truck.

Patented Nov. 16, 1831.

Post Office Newmarket, Hampshire, Virginia

Letters Patent

6842X

The subject referred to in these Letters Patent and making part of the same containing a description in the words of the said Lewis Morris himself of his improvement called Morris's self regulating self driving Rail Road Car.

It is known that S. Lewis Morris of Hampshire County of Westmoreland State of Virginia have made improvement being self regulating self driving Rail Road Car which is described as follows. This Rail Road car consists of the following parts. 1. The flange wheel with their axle. 2. The horizont and guiding pole. 3. The frame on which the carriage is placed. 4. The friction wheel or roller.

1. The flange wheel with their axle. - Four of the flange wheels are made in the usual form, but without a cone. Two light wheel, called regulating wheels are placed on the axle of the carriage, one made about 10 or 11 inch or $3\frac{1}{2}$ of an inch between the flanges or shoulder of the axle longer than the axle of the main wheel. This is done to make the regulating wheels not quicker. One of the regulating wheels, as well as one of the main wheels is made stationary and the other revolves on the axle, to accommodate themselves to the curve. On the regulating axle are one or two flanges projecting from the body of the axle to give the center about $\frac{3}{4}$ of an inch embraced by a metal box made in halves in the form of a T both ways from the center, and secured together so as to let the axle to be made firmly and hold well. On the axle of the other wheel might be made stationary and both the wheels made to revolve. The main wheels are made as usual, but the regulating axle must be made quite light. On this frame are suspended two sliding bars in which the regulating axle turns. They are made to slide up and down so as to prevent the flanges from being injured by any irregularities in the track road. The bars of the main axle are suspended and

The roads bear the usual way - 2. The frame and guiding pole
These are made as usual in a common wagon. The guiding pole is made in two equal parts, and united ~~by~~ ^{to} the back
being inclosed in an oblong rib or mantles, with holes in the
same size in the T about $1\frac{1}{2}$ inch apart to admit of a bolt
for determining the quickness or slowness of the frame for regulating
the carriage in the curve according to the desire of the conductor of the car-
riage - 3. The platform on which the carriage is placed. This may
be made curved or straight in the usual mode, and of any convenient
length. On the side of this frame is hung a box, with a moveable joint
the beam to be of any convenient length and strength. On the end of this
beam is a metal box, which embraces the middle axle box at each
end in which it moves or slides, and always ^{up} ~~up~~ will keep the main
axles in a proper position for forming the loop. The box embrac-
ing the end of the axle box may be hung with a chain from the frame
so that the regulating wheels may ^{be} ~~be~~ ⁱⁿ ~~in~~ a straight line, and the
flange only touch the iron rail when it is required to move in a curve -

4. The friction wheels or rollers. These are all friction wheels placed
at each end of the carriage under the bolster to make the regulating
but more easy. Any kind of friction rollers for the main rail's turn
in may be used at pleasure. Operation - When the Rail Road is straight
then the wheels all move parallel to each other, but when the carriage comes
to a curve in a curve the flange of the regulating wheel comes in contact
with the iron rail and instantly, however, the centre of the guiding pole out of
a straight line, and then turns the four hind wheels, and keeps
them to the centre of the radius of the loop of the curve. Thus moving
the carriage in its course without any additional power, and without
any injury to the rail. As the wheel can be placed ^{at} ~~at~~ any ^{desired} ~~desired~~
height and the carriage made of any length, long distances or any num-
ber of passengers, can be moved without inconveniences.

That it claim as my invention and wish to be secured by letters patent is the
above described method of making Rail Road carriages with self-regulating
or self-directing wheels and axes. How ever applied, the right described

5872A 297

principle for guiding Rail Road carriages may also be applied to Go
carting Engines in McAdamized and other Roads by means of that
an Opinion of Policy and could, in by any other means adopted to the purpose
for a further illustration of my invention refers to the model and
drawings of the same deposited in the Patent Office. (In testimony
whereof I have caused to subscribe my name before two witnesses at the
City of Washington this 10th day of November 1831)
